GAME

Joseph C. Gillespie, Washington, D. C.

Application December 30, 1938, Serial No. 248,622

5 Claims. (Cl. 273—2)

This invention relating as indicated to games is more particularly directed to an indoor marble game played upon a marked off horizontal surface. The marbles are adapted to be racked to 5 form an open V and the shooter assumes a shooting position opposite to such V. The horizontal surface is provided with pockets into which the balls or marbles are impelled and the surface is surrounded by a raised border somewhat 10 in the nature of a retaining wall so as to retain the marbles upon the surface. Various games can be played as will be described more in detail hereinafter.

A more definite object of the invention is to 15 provide a simple, inexpensive game played without mechanical accessories such as cues, wherein ordinary marbles may be used so that the games does not become inoperative by the loss or destruction of any of its parts.

20 The game apparatus may be formed of wood, metal, papier-mâché, cardboard or equivalent material. In its more expensive form the horizontal surface may be covered with felt which is appropriately marked and the retaining wall 25 may be provided with cushioning material such as sponge rubber or the like but neither of these are necessary.

In another embodiment the playing surface and retaining wall may be formed of metal and 30 in this instance the metal of the surface can be extruded to form pockets which also serve as supporting legs.

To the accomplishment of the foregoing and related ends, said invention, then consists of the 35 means hereinafter fully described and particularly pointed out in the claims; the annexed drawing and the following description setting forth in detail certain mechanism constituting, however, but one of various applications of the 40 principles of my invention.

In said annexed drawing:

Fig. 1 is a plan view taken from above.

Fig. 2 is an elevational view of Fig. 1.

Fig. 3 is a partial vertical section taken on the 45 line 3—3 of Fig. 1.

Fig. 4 is a perspective view of the rack.

Fig. 5 is a composite view of three of the balls or marbles used in playing the game.

Fig. 6 is a partial vertical section taken on line 50 6—6 of Fig. 1 and

Fig. 7 is a central vertical section of a modification.

Referring now to the drawing and more particularly to Fig. 1 it will be seen that my game 55 apparatus comprises a table-like member hav-

ing a horizontal base 1 to which is attached a raised border or retaining wall 2, such attachment being made through the medium of screws or other joining means. The base 1 is preferably but not necessarily covered with a felt surface 3 10 and the base as well as the felt are apertured to receive pockets 9, 10, 11 and 12. The entire apparatus is supported upon legs 5, 6, 7 and 8 and it is, of course, optional to provide more legs and more pockets. The felt surface 4 has im- 15 printed or otherwise applied thereto a marking in the form of an open V 13. This marking comprises two relatively wide bars meeting at an angle somewhat in the form of a chevron and is located closely adjacent the letter N which in 20 turn is closely adjacent the pocket 10. A dot 14, preferably round, is located adjacent the letter S, which it will be noted, adjoins the pocket 12 which is opposite the pocket 10. It will also be observed that the angle of the open V mark- 25 ing 13 extends toward the shooter's position 14. The table also contains a circular marking 15 which is concentric with the rim or retaining wall 2 and the circle thus described is bisected by lines 16 and 17 to form four quadrants. The 30 pockets are designated E, W, N, and S, the words being abbreviated as shown. This is done in order to name any particular pocket into which the shooter hopes to impel a marble.

A number of different games can be played with 30 this apparatus and in all of these the marbles, which are numbered from 1 to 17, are racked up by means of the rack generally indicated by the numeral 17 in Fig. 4. This rack comprises a hollow V shaped member having end walls 21 35 and 22, outer walls 18 and 21 and inner walls 19 and 20. The rack is placed over the marking 13 and if it is desired to play the game in its simplest form the marbles 1 to 17 are placed in the rack indiscriminately. The shooter then 40 places his knuckle on the marking 14 and attempts to shoot various marbles into the different pockets. If it is desired to play rotation the marbles are racked up so that the ball numbered 1 is placed at the apex of the V and the adjoin- 45 ing balls increase progressively to the ends of the broad bands forming the V. The shooter then attempts to first knock the ball marked 1 into a pocket and if he misses, the next shooter takes his turn, stopping when he has missed, it being 50 understood that the balls are used in numerical order.

Stated more definitely the marbles are racked into position, the first player then shoots the white or plain marble with his thumb from the 55

dot near the south pocket. The player or succeeding players then continue to shoot from the place where the plain or shooter marble stops.

If the plain or shooter marble should fall into a pocket or jump from the table the player loses his turn and any numbered marble made on that play must be returned to the V. The next player then places the plain or shooter marble on the spot 14 and proceeds as before, with the exception that he may shoot at marbles only within the circle and north of horizontal line 16 running from E to W. In the event there are no marbles within the circle north of the horizontal line, the marble nearest to starting spot 14 is then placed on the apex of the V and the player then proceeds to shoot at it.

If the player should knock a numbered marble off the table the marble is then placed on the V and the next player proceeds to shoot from the position upon which the shooter stops. If the player should knock the last numbered marble off the table or into a pocket other than the one specified the marble is then returned to the apex of the V and the next player proceeds to shoot from the starting spot.

A further game may be played known as nine-ball and in this case the 9 ball itself is placed upon the apex of the open V and balls numbered from 10 to 17 are aligned along one leg of the marking 13. Balls numbered 1 to 8 are placed along the other leg and each shooter then attempts to impel the balls along one leg into a pocket, shooting at the 9 ball last. This game is, of course, for two players only.

In Fig. 7 I have shown a modification composed of metal. In this embodiment of the invention the surface 31 is not provided with felt and the retaining wall 30 may be integrally formed therewith. Likewise, the pockets 33 and 34 may be pressed out of the playing surface 31 to provide a relatively inexpensive game. If desired the pockets may be separately attached as is the case with pocket 35 and it will be understood that additional pockets may be provided as necessary. Pocket 35 is illustrated as being welded at 32 but may be secured in any other desired manner. The pockets in the Fig. 7 modification are preferably deep and flaring so as to entrap a ball propelled thereinto as otherwise the balls or marbles would have a tendency to bounce out of the pocket.

From the foregoing description it will be seen that I have provided a game which will afford ample amusement and will render it possible to play marbles in an entertaining manner in the interior of living quarters. This makes it possible for a child to play an entertaining game indoors when inclement weather prevails.

It will also be seen that I have provided a game which employs no expensive accessories, such as cues and the like and all the moving parts may be readily replaced at very small cost. This last result is obtained because conventional marbles of different colors may be easily numbered and used when any of the original marbles have become lost or destroyed. There have been many marble games used in the past but in most of these when one part becomes lost the game is rendered inoperative. In my game this is impossible because of the ease and small expense attached to replacing the marbles. My game differs from other games involving mechanical cues in that it is strictly a game of skill whereas such other games are merely games of chance and rapidly lose their appeal.

Other modes of applying the principle of my invention may be employed instead of the one explained, change being made as regards the means and the steps herein disclosed, provided those stated by any of the following claims or their equivalent be employed.

I therefore particularly point out and distinctly claim as my invention:

1. In a device of the character described, a horizontal playing surface, a retaining wall surrounding said surface and extending vertically above it, pockets in said surface adjacent said wall, indicia on said surface adjacent each pocket and a positioning mark upon said surface comprising two broad bands meeting at an angle in a color contrasting to that of said surface, said mark being located adjacent one of said pockets, and another mark indicating a shooter's position, said last named mark being located adjacent a pocket opposite to said first named pocket, said positioning mark being adapted to receive marbles aline in an open V formation.

2. In a device of the character described, a horizontal playing surface, a retaining wall surrounding said surface and extending vertically above it, pockets in said surface adjacent said wall, indicia on said surface adjacent each pocket and a positioning mark upon said surface comprising two broad bands meeting at an angle in a color contrasting to that of said surface, said mark being located adjacent one of said pockets, and another mark indicating a shooter's position, said last named mark being located adjacent a pocket opposite to said first named pocket, the angle of said first named mark pointing toward said last named mark, said positioning mark being adapted to receive marbles aline in an open V formation.

3. In a device of the character described, a horizontal playing surface, a retaining wall surrounding said surface and extending vertically above it, pockets in said surface adjacent said wall, indicia on said surface adjacent each pocket and a positioning mark upon said surface comprising two broad bands meeting at an angle in a color contrasting to that of said surface, said mark being located adjacent one of said pockets, and another mark indicating a shooter's position, said last named mark being located adjacent a pocket opposite to said first named pocket, the angle of said first named mark pointing toward said last named mark, said surface being supported upon a number of legs, each of which has a length greater than that of said pockets, said positioning mark being adapted to receive marbles aline in an open V formation.

4. In a device of the character described, a horizontal playing surface, a retaining wall surrounding said surface and extending vertically above it, pockets in said surface adjacent said wall, indicia on said surface adjacent each pocket and a mark upon said surface comprising two bands meeting at an angle, to form an open V in a color contrasting to that of said surface, said surface and wall having a circular configuration and said surface having a circle marked thereon, a shooter's mark on said circle diametrically opposite to said first named mark, said circle being concentric with said wall the ends of said first named mark terminating upon said circle and the apex of said V being within said circle.

5. In a device of the character described, a horizontal playing surface, a retaining wall surrounding said surface and extending vertically above it, pockets in said surface adjacent said

wall, indicia on said surface adjacent each pocket and a mark upon said surface comprising two bands meeting at an angle, to form an open V in a color contrasting to that of said surface, said surface and wall having a circular configuration and said surface having a circle marked thereon, a shooter's mark on said circle diametrically op-

posite to said first named mark said circle being concentric with said wall, and said circle being marked off in quadrant lines with one of said quadrant lines passing through the apex of said V.

JOSEPH C. GILLESPIE.
